UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

DESIGN FOR A LOCK-CASE.

SPECIFICATION forming part of Design No. 30,894, dated May 30, 1899.

Application filed February 20, 1899. Serial No. 706,266. Term of patent 14 years.

To all whom it may concern:

Be it known that I, HENRY G. VOIGHT, a citizen of the United States, residing in New Britain, in the county of Hartford and State 5 of Connecticut, have invented and produced a new and original Design for a Lock-Case, characterized by an ornament thereon, of which design the following is a specification, reference being had to the accompanying 10 drawing, in which the figure shows in full lines an ornament of my design as worked into a lock-case of an old form, the said lock-case being indicated by broken lines.

The only thing in connection with the design shown that I have invented is the impression or ornament upon the broad sides of the lock-case, which lock-case, aside from the said impression, has long been old and well known, and hence is in no sense of my invention.

The central feature of my design is a circular figure *a*, from the right of which there extends three pointed beads, one being the central point *4* and the other two the points *5* on either side of the central point *4*. This central point has a sunken recess or triangular panel, as at *6*. On the left of the circular figure *a* there are two beads *7*, one side of said beads being a continuation of one side 15 of the points *5*, while the other side of each

of said beads is in alignment with one side of the panel *6*. Above and below the ornamental figures thus far described are other pointed beads *8* *9* *10* *11* of gradually decreasing lengths. The bases of all the points and beads 35 above and below the beads *7* merge into each other and extend on one line along the front edge of the broad side of the lock-case to which my ornament is applied. Two lines intersecting the sharp or small ends of the points *4* *5* *8* *9* *10* *11*, in connection with the base-line of said points, include a triangular figure, in which the several ornaments or features blend into a single composite ornament of triangular form made up of smaller and 45 sharper triangular figures or pointed beads surrounding the central circular figure, as shown.

The words "above" and "below" and "right" and "left," &c., are used with reference to the lock-case when in the position shown.

What I claim, and desire to secure by Letters Patent, is—

The design for a lock-case having the ornament thereon as herein shown and described.

HENRY G. VOIGHT.
